UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

BUCKET EXCAVATOR.

1,160,572.

Specification of Letters Patent.

Patented Nov. 16, 1915.

Application filed June 6, 1910. Serial No. 565,220.

To all whom it may concern:

Be it known that I, MORTON G. BUNNELL, a citizen of the United States of America, and resident of Chicago, Cook county, Illinois, have invented a certain new and useful Improvement in Bucket Excavators, of which the following is a specification.

My invention relates to excavators of that kind in which a runway is provided for excavating buckets or scoops, which runway is provided with a curve or bend which enters the ground, whereby the said scoop or bucket moves downward and then upward, the curve or bend in the runway being such that the edge 15 of the bucket or scoop does not, at such time, assume the most efficient cutting angle, but stands at such an angle that it simply scrapes, which is particularly objectionable when the excavator is working in hard 20 ground.

The object of my invention is to provide an improved cutter which will travel ahead of the bucket or scoop, which will work as well, and possibly better, during the portion 25 of its travel where it passes around said curve or bend in the runway, thus insuring an efficient cutting action at all points in the path of the bucket or scoop, especially at the curve or bend where ordinarily the position 30 of the bucket or scoop is such that its edge does not assume a correct cutting angle, and which will run in the same tracks of the runway that are provided for the wheels of the bucket or scoop, without any sliding or 35 other movable connections between the cutter and the wheels thereof.

To this and other useful ends, my invention consists in matters hereinafter set forth and claimed.

In the accompanying drawings, Figure 1 is 40 a front elevation of the lower portion of a runway, showing the curve or bend therein, and showing also a bucket or scoop with a cutter in front thereof, both the bucket or scoop and the cutter traveling in one and the same runway, and said cutter involving the principles of my invention. Fig. 2 is an enlarged section on line 2—2 in Fig. 1, looking 45 at the rear of said cutter. Fig. 3 is a side elevation of the cutter shown in Fig. 2.

As thus illustrated, the runway A may be 50 of any suitable character, and has a curve or bend *a* at the bottom of the ditch. The bucket or scoop B has front and rear wheels *b* and *b'* that run in the tracks of said run-

way. It will be seen that the said front wheels *b* are some distance ahead of the rear wheels, whereby the bucket while rounding the curve or bend assumes a position that makes the edge of the cutting blade *b* 60 scrape instead of cut—that is to say, the edge at such time does not assume its most efficient cutting angle. This is objectionable, especially in hard ground, as the bucket or scoop is subjected to unnecessary strain, 65 and is liable not to properly collect its load.

To obviate this difficulty, the cutter C is arranged to travel ahead of the bucket or scoop and loosen up the dirt. The said cutter is triangular in shape, having front and rear wheels *c* and *c'* that run in the runway, and a blade *c* that cuts the ground ahead of the bucket or scoop. The shape of the cutter C is such that while rounding the curve or bend, as shown in Fig. 1, the edge of the 75 blade *c* is on a line drawn from the axis of curvature of the runway through the axis of the wheels *c'*, which is the correct angle for cutting. Preferably, the cutter is connected with the front of the bucket or scoop B by 80 means of links D, and has links E for connection with the operating rope or cable. It will be seen that the blade *c* is always the proper distance from the runway, so as to cut properly in front of the bucket or scoop, 85 and that no sliding or other connections are necessary between said blade and the upper or wheeled portion of the cutter. Thus the whole cutter structure is very strong and rigid. The angle of the blade *c* is even 90 better while rounding the curve, as at such time it is a little farther away from the bucket or scoop, and is down a little flatter on the surface of the ground. In this way the cutter C works effectively at the time 95 when it is most necessary for it to do so, which is when the bucket is forced to assume its impaired angle for cutting. As shown, the cutter C is bail-shaped and, like the bucket or scoop, arranged to travel between 100 the two sides of the runway. The cutter serves as a link in a chain or series of links by which the line of draft is kept in line with the runway, even while the bucket or scoop is rounding the curve. This makes 105 the same run easier and smoother.

It is obvious that my invention is applicable to runways of different shapes. In other words, the runway is not necessarily of the shape here shown, as any runway in 110

which that portion which enters the ground is curved is liable to produce the difficulty previously stated. By my invention, however, such difficulty is obviated, as wherever the bucket goes around a curve or bend it is preceded by a cutter, and the exact angle of the bucket at such time is unimportant. Also, my invention is applicable to any excavator having one or more buckets, regardless of the method of operation thereof.

By this arrangement the bucket and cutter travel in the same runway, and while the curve or deflection in the runway impairs the cutting angle of the bucket, such curve or deflection does not impair the cutting angle of the cutter. Thus the bucket can be of greater length and capacity than without the cutter.

I do not limit myself to the exact construction shown and described.

What I claim as my invention is:

1. In an excavator, a runway having tracks, a bucket adapted to travel thereon, a cutter traveling on the said runway, links connecting the cutter with the bucket, and links connected to the front of the cutter, to keep the draft in line with the runway, all of said links traveling in the tracks of the runway.

2. In an excavator, a runway having a curve therein, a wheeled bucket adapted to travel thereon, said bucket having a relatively long wheel base, whereby its cutting angle changes objectionably while rounding said curve, and a cutter traveling in front of the bucket, said cutter having a blade the edge of which is on a line drawn from the axis of curvature, a set of wheels the axis of which is also on said line, and another

set of wheels the axis of which is a distance 40 from the first wheels, the two axes of said wheels bearing a fixed relation to each other, and being a relatively short distance apart, whereby the cutting angle of said cutter does not change objectionably while rounding 45 said curve.

3. In an excavator, a runway having a curve therein, a wheeled bucket adapted to travel thereon, of a length to impair the cutting angle thereof while rounding said 50 curve, a cutter for loosening all the dirt in advance of the bucket, traveling on the same runway, and means whereby the cutter has a better cutting angle while rounding 55 the curve than while traveling straight ahead.

4. In an excavator, a runway with a curve therein, a wheeled bucket adapted to travel on said runway, having a wheel base, of such length that its cutting angle changes 60 objectionably while rounding said curve, a bail-shaped cutter for loosening all the dirt in front of said bucket, having triangular-shaped sides, and front and rear wheels for the upper corners of said sides, the wheel 65 base of the cutter being of a length to prevent undesirable variation of the cutting angle and a consequent loss of cutting efficiency thereof while rounding said curve, thereby enabling said bucket to fill easily 70 while operating at the wrong angle for cutting.

Signed by me at Chicago, Illinois, this 11th day of May, 1910.

MORTON G. BUNNELL.
